BOTTLE STOPPER

Axel Moeller, Racine, Wis.

Application August 18, 1941, Serial No. 407,270

4 Claims. (Cl. 215—53)

This invention appertains to bottle stoppers, and more particularly to bottle stoppers of the expansible type, and is an improvement on my bottle stopper shown in my pending application Serial No. 283,524, filed July 10, 1939.

One of the primary objects of my present invention is to provide means for producing a positive seal between the compressible body of the stopper and the interior of the bottle neck, when the stopper is in its operative position, whereby the leakage of liquid and gas will be absolutely precluded.

Another salient object of my invention is to provide means on the compressible body of the stopper for contact with the interior of the bottle neck, so that when the body is compressed a firm grip will be had by the stopper on said neck, whereby the blowing of the stopper by gas under pressure in said bottle will be prevented.

A further important object of my invention is to produce a vacuum seal between the compressible body of the stopper and the bottle neck, whereby to bring about the positive seal and to prevent the blowing of the stopper from the bottle.

A still further important object of my invention is the provision of a bottle stopper including a compressible body having formed thereon spaced annular neck-engaging ribs defining annular channels therebetween, with means for compressing the body longitudinally to expand the body circumferentially, so as to force the ribs toward one another and to flatten the ribs against the bottle neck, with means for then slightly releasing the longitudinal compression of the body to allow slight expansion of the ribs, the expansion of the ribs functioning to permit enlargement of the channels, whereby a suction is formed in each channel to create a vacuum against the inner wall of the bottle neck.

With these and other objects in view, the invention consists in the novel construction, arrangement, and formation of parts, as will be hereinafter more specifically described, claimed, and illustrated in the accompanying drawing, in which drawing:

Figure 1 is a side elevational view of my improved stopper, showing the same in the neck of a bottle but in its released, unlocked position, the bottle neck being shown in dotted lines.

Figure 2 is a view similar to Figure 1, but showing the stopper in section, and with the compressible body in its greatest expanded condition, the cam lever being on the high point of its cam.

Figure 3 is a view similar to Figure 2, but showing the cam lever in its completely locked position, with the high point thereof past the center of the stopper, so as to allow a slight contraction circumferentially of the compressible body.

Figure 4 is a top plan view of the stopper, with the cam lever in its lowered locked position.

Figure 5 is a sectional view through the stopper, taken on the line 5—5 of Figure 3.

Referring to the drawing in detail, wherein similar reference characters designate corresponding parts throughout the several views, the letter S generally indicates my improved stopper, and N the neck of a bottle with which the stopper can be associated.

The general construction of the stopper S is similar to that shown in my pending application above referred to, and, hence, the same includes 20 a compressible body portion 6, which can be formed from rubber or similar material. The body is provided with a longitudinally extending axial bore 7.

The lower end of the compressible body 6 is engaged and supported by a bottom cone plate 8, which can be stamped from sheet metal of the desired gauge. Rigidly secured to the axial center of the cone plate 8 is a threaded stem 9. This stem extends loosely into the bore 7 of the compressible body, and the upper end of the stem is received in an elongated internally threaded sleeve 10. The sleeve extends exteriorly of the body 6 and has slidably mounted thereon a top pressure plate 11. The pressure plate 11 is of a greater diameter than the cone plate 8 and, preferably, has formed on its periphery an arcuate outstanding annular flange 12 for engaging over the upper surface of the top bead of the bottle neck N. Thus, the central part of the pressure plate 11 is somewhat depressed so as to extend into or flush with the top of the bottle neck. This allows the rubber body 6 to extend entirely within the bottle neck. If so desired, the pressure plate and the cone 8 can be formed from colored plastic material.

Disposed above the pressure plate 11 is a cam lever 13. This cam lever 13 is connected to the upper end of the sleeve 10 by means of a crosspin 14. As illustrated, the cam lever is also struck from a single piece of sheet metal, and the same is of a substantial U-shape in cross section for embracing the upper end of the sleeve. The outer end of the lever has formed thereon an angularly extending manipulating fingerpiece 15, while the inner end of the lever has formed thereon cam

lips 16, which are adapted to engage the upper edge of the pressure plate 11 when the cam is being swung to its lowered position for raising the bottom cone plate 8.

As the cam lever 13 is swung down (see Figure 2), the sleeve 10 and the threaded stem 9 are pulled up toward the pressure plate 11, and the pressure plate is held tight against the bottle neck. Thus, the body 6 is compressed longitudinally and the body will expand circumferentially. The body 10 is expanded circumferentially to its greatest extent when the high point of the cam lip 16 engages the pressure plate, as is best shown in Figure 2, and when the high point of the cam lips ride past the axial center of the stopper (see Figure 3), the compressible body will be slightly contracted circumferentially, for a purpose which will later appear.

In accordance with my present invention, I form on the outer surface of the compressible body 6 spaced annular outstanding ribs 17, and these ribs define annular channels 18 therebetween. The ribs are provided, preferably, with flat outer peripheries for engaging the interior of the bottle neck.

In use of the stopper, the stopper is inserted in the bottle neck, while the cam lever is in its raised position, as is clearly shown in Figure 1, and as the compressible body is expanded longitudinally, the stopper can be quickly and conveniently inserted within the bottle neck. As the cam lever 13 is swung down and the body 6 is compressed longitudinally and expanded circumferentially, the ribs 17 will be brought toward one another and flattened against the inner surface of the bottle neck, as is clearly shown in Figure 2, and the body is compressed longitudinally to its fullest extent when the high point of the cam lip 16 engages the pressure plate 11, and when the high point of the cam lip 16 is in longitudinal alignment with the axial center of the stopper. As the high point of the cam lip 16 rides past the center of the stopper (see Figure 3) and the compressible body is slightly expanded longitudinally, a slight contraction circumferentially of the compressible body 6 is permitted, and, consequently, the annular ribs 17 will enlarge in their effort to assume their normal configuration. Hence, when the ribs enlarge, a suction is created in the annular channels 18 against the wall of the bottle neck, which forms, in effect, a vacuum seal which positively holds the stopper against blowing out when gas pressure is created in the bottle.

By my improved construction, not only is a perfect tight seal formed, but also a desired grip is 55

had by the stopper on the bottle neck, so that the stopper cannot be forced out of the bottle.

Changes in details may be made, which do not depart from the spirit and scope of my claims, and what I claim as new is:

1. In an expansible stopper including, an elongated compressible body having an axial bore extending therethrough, means for compressing the body longitudinally and expanding the same circumferentially, and annular spaced ribs formed on the outer surface of the body defining air suction channels therebetween.

2. In a stopper, an elongated compressible body, spaced annular ribs formed on the outer surface of the body defining air suction channels therebetween, and means for compressing the body longitudinally to expand the same circumferentially, whereby to flatten said ribs against the inner surface of a bottle neck.

3. In a bottle stopper, an elongated compressible body, spaced annular ribs formed on the outer surface of the body defining annular channels therebetween, and means for initially compressing the body longitudinally to expand the body circumferentially, whereby to force and flatten said ribs against the inner surface of a bottle neck, and, secondly, to slightly release the compression of the body longitudinally, whereby to allow slight expansion of the ribs to create a suction in said channels on said bottle neck.

4. In a stopper, an elongated compressible body having an axial bore extending therethrough, a bottom cone plate engaging the lower end of the body, a threaded stem having its lower end firmly anchored to the axial center of the cone and extending into said bore, an elongated internally threaded sleeve receiving the upper end of the stem and extending into said bore, a pressure plate slidably mounted on the sleeve for engaging the upper edge of a bottle neck and the compressible body, a swinging cam lever pivotally associated with the upper end of the sleeve, having a cam for contact with the upper face of the plate, and spaced annular ribs formed on the outer surface of the compressible body defining annular channels therebetween, said ribs being compressed to their maximum extent against the inner surface of the bottle neck, when the cam of the cam lever engages at its high point the upper surface of the plate, said ribs being slightly expanded to create a suction in said channels when the high point of the cam rides past the axial center of said body.

AXEL MOELLER.
